UNITED STATES PATENT OFFICE.

GEORGE H. M. DAHL, OF WASHINGTON, DISTRICT OF COLUMBIA.

MACHINE FOR MAKING PRINTERS' RULES AND LEADS.

Application filed March 18, 1925. Serial No. 16,513.

My said invention relates to a machine for making printers' leads and rules and it is an object thereof to provide a device of this character which shall form leads better and more satisfactory in use than those heretofore known. Various machines have been devised for this purpose but they are ordinarily defective in that air gets into the compartment through which lead is forced into the mold and is trapped in the mold which gives rise to weak places in the leads and rules and it is found that they break at these weak places.

A further object of the invention is to provide a machine in which, by means of a slight change of parts leads and rules of various thickness can be molded, the character of the attachment being such that a change in thickness can be made very quickly and by unskilled workmen.

Still another object is to provide a continuous flow mold for leads and rules.

Referring to the accompanying drawings which are made a part hereof and on which similar reference characters indicate similar parts,

Figure 1 is a side elevation of my device,

Figure 2, a vertical section at right angles to Figure 1,

Figure 3, a detail of pistons used in the device,

Figure 4, a side elevation of the molding devices on an enlarged scale,

Figure 5, an elevation at right angles to Fig. 4,

Figure 6, a section on line 6—6 of Fig. 4,

Figure 7, a plan of the mold,

Figure 8, a side elevation of a block shown in various other figures, and

Figure 9, a detail of a closure for the vent at the bottom of the pot.

In the drawings reference character 10 indicates a melting pot for type metal or other metal used in the printer's trade, this pot being of ordinary form and being used to melt metal for various purposes. A jacket 11 surrounds the pot which is supported by means of legs in conventional manner and a vent 12 is provided at the top of the space between the pot and the jacket to permit escape of exhaust gases from the flame by which the pot is heated. Gas for this flame is provided by a pipe 13 arranged in annular form underneath the pot.

Within the pot an angular frame, here in-

dicated as of rectangular conformation in plan, is secured to the bottom of the pot as by means of screws 15 extending through such bottom or it may be made in one piece with the pot. This flange is L-shaped in section as clearly shown in Figure 1 and has a vertical flange 14 and a horizontal flange 14'. A closed chamber is provided at 16 preferably by means of an inverted member 17 having integral sides, ends and bottom, said member being also provided with a lateral flange 18 resting on the upright flange 14. The rim 19 of said member fits into the frame at the inner side of the flange 14 and rests on the horizontal flange 14' thus forming a liquid-tight closure.

Three cylinders 20 are set into the bottom (which in the inverted position forms the upper part) of the member 17 and are secured in position in any suitable manner. 75 These cylinders may, of course, be made integral with the member 17 if desired. Pistons 21 are movable up and down in the cylinders 20. These pistons are operated by means of cams 22 on a cam shaft 23 acting against followers 24 on the depending arms 25 of bent levers having laterally extending arms 26 pivotally attached to connecting rods 27 which are pivoted in turn to rods 28 extending through caps 29 closing upwardly-opening recesses in the pistons. The followers 24 may be held against cams 22 by springs 24' or otherwise.

The rods 28 are provided with heads 30 and coil springs 31 are positioned about the rods between said heads and the caps 29, these caps being rigidly secured to the pistons in any suitable manner. The yieldable connection permits positive limitation of the upward movement of the pistons and such limitation is provided by fixed abutments 32 on the cylinders coacting with abutments 33 on the pistons to arrest positively the upward movement of the pistons. One purpose of such limitation is to insure that the melted metal in the pot will be permitted to flow into the chamber 16 at the end of the upward stroke of each piston. For this purpose the pistons are provided at their lower ends with recesses 34 having radial passages 35 communicating therewith and extending to the outer wall of the piston or to one of the ring grooves 36 formed in the head of the same. An orifice at 37 in each cylinder provides for communication with 110

the chamber 16 through the passage 35 and recess 34 when the piston is at the upper end of its movement.

It should be noted at this point that the abutments 33 are formed at spaced intervals about the stem of the piston for the reason that a continuous bearing surface between the piston and the cylinder is impracticable as the metal will become set between such continuous adjacent surfaces and so will clog the piston and stop its movement.

At the lower end of each cylinder a float valve 38 is provided by means of which the molten metal is permitted to move in one direction only. This float valve may be of cast iron so as to float on the melted metal in the chamber and as seen in Fig. 3 it is guided by a spur 39 on a rod 40 extending across the chamber and secured thereto at its ends in any convenient manner, the spur 39 extending up into a recess 41 in the float valve. When the piston moves downward as at the right-hand side of Fig. 3 the float valve will be forced down by the metal in the cylinder which has entered through port 37, passage 35 and recess 34. When the piston moves upward the float valve will immediately close the cylinder as at the left-hand side of Fig. 3.

30 The cylinders and pistons and the operating means for the pistons are illustrated as being three in number and it is intended in all cases that there shall be more than one though the number may be varied if desired. 35 One purpose in providing three pistons is that this enables the machine to keep up a constant flow of metal into the chamber 16 and hence to the mold which is one means for preventing access of air to the chamber 40 and therefore to the mold. In machines of the prior art a single piston has been employed and hence there could not be a continuous flow of molten metal. The metal passes from the chamber to the mold 45 through a small threaded port 42 in the bottom of the pot this port being preferably directly in line with the middle cylinder. By such construction the port can be closed, as when it is necessary to have access to the mold for repairs or for other purposes, by merely removing the central piston and inserting a rod 43 down through the cylinder the rod having a threaded end 44 to be screwed into the threaded port 42 and effectively shut off the flow of metal.

45 The screws 15 in addition to holding down the angular frame 14 also serve for attachment to the bottom of the pot of a block 46 forming the upper member of the mold. 50 This block is provided at 46 with an aperture registering with the port 42 which aperture may be of smaller size and shape or may be flared out at the lower end or otherwise be of different shape. A pair of blocks 47 and 48 are secured to the block

45 by means of screws 49, these blocks forming the sides of the mold. A block 50 is held between the blocks 47 and 48 in fixed relation thereto by means of screws 51, this block abutting at its upper end against block 45 and being secured thereto if preferred. A block 52 is adjustably mounted between the blocks 47 and 48 and provides with the other members of the mold a mold chamber 53 of uniform length and width and variable in thickness by movement of the block 52.

55 For purposes of adjustment the blocks 47 and 48 are provided with rows of holes at 54, each of said holes being adapted to register with one of the holes in a row at 55 on the block 52. The rows 55, as will be seen in Fig. 4, are arranged diagonally and therefore movement of the block 52 toward and from the block 50 will position successive holes in registry with each other after which pins 62 can be thrust through the registering holes to maintain the adjustment. Thereafter the block 52 is securely locked in place by means of screws 56. The block 45 is made detachable, among other reasons, so that a mold for making rules can quickly be substituted for a mold for forming leads and vice versa, it being only necessary to stop the outlet of the chamber by means of the rod 43 in Fig. 9 and then remove a few screws to take off the mold that is in use.

59 It is essential that the mold be cooled to cause the metal to set quickly and for this purpose each of the blocks 50 and 52 is provided with a series of vertical passages 57 communicating at the lower end with a transverse passage 58 supplied with water or other cooling fluid by a pipe 59. At the upper end there is a similar transverse passage 60 communicating with an outlet pipe 61. These transverse passages are closed at the ends by means of plugs in well-known manner as are also the vertical passages at their lower ends except one which communicates with the pipe 61.

65 It will be obvious to those skilled in the art that various changes may be made in my device without departing from the spirit of the invention and that fluid metal may be shaped thereby for other purposes, and therefore I do not limit myself to what is shown in the drawings and described in the specification but only as indicated in the appended claims.

Having thus fully described my said invention, what I claim as new and desire to secure by Letters Patent, is:

70 1. A machine for making printers' leads and rules comprising a melting pot, a closed chamber therein, a mold underneath the chamber, a straight passage extending through the bottom of the melting pot and the mold, and a plurality of pistons operat-

- ing in timed relation to force molten metal movement of said metal, substantially as set through the chamber in a continuous flow, forth. substantially as set forth.
2. A machine for making printers' leads and rules comprising a melting pot, a closed chamber therein, a mold attached to the bottom of the pot, a passage through said bottom leading to the mold said passage communicating with the chamber, a plurality of cylinders communicating with the pot and the chamber, pistons in the cylinders, rods connected to the pistons, means for moving the rods positively upward and yieldingly downward, positive means for limiting the upward movement, and passages leading from the pot through the cylinder and piston to the lower end of the cylinder when the piston is fully retracted, substantially as set forth.
- 20 3. A machine for making printers' leads and rules comprising a pot, a closed chamber, a cylinder communicating with the pot and the chamber, and a piston in the cylinder having guiding lugs for engagement with the cylinder wall, substantially as set forth.
4. A machine for making printers' leads and rules comprising a pot, a closed chamber, a cylinder communicating with the pot and the chamber, a piston in the cylinder having guiding lugs for engagement with the cylinder wall, yieldable means for retracting the piston, and abutments on the cylinder wall adapted to engage said lugs for limiting such retracting movement, substantially as set forth.
5. A machine for making printers' leads and rules comprising a pot, a closed chamber, a cylinder communicating with the pot and the chamber, a piston in the cylinder having guiding lugs for engagement with the cylinder wall, yieldable means for retracting the piston, abutments on the cylinder wall adapted to engage said lugs for limiting such retracting movement, a recess at the lower end of the piston and registering orifices in the piston and the cylinder wall providing a passage from the pot to said recesses when the piston is in its retracted position, substantially as set forth.
- 45 6. A machine for making printers' leads and rules comprising a melting pot, a chamber, a cylinder leading into the chamber, means for forcing metal from the pot into the chamber through said cylinder, and a floating valve at the lower end of the cylinder for preventing return movement of said metal, substantially as set forth.
7. A machine for making printers' leads and rules comprising a melting pot, a chamber, a cylinder leading into the chamber, means for forcing molten metal from the pot into the chamber through said cylinder, and a floating cast iron valve at the lower end of the cylinder for preventing return
8. A machine for making printers' leads and rules comprising a melting pot, a chamber, a cylinder leading into the chamber, means for forcing metal from the pot into the chamber through said cylinder, a floating valve at the lower end of the cylinder for preventing return movement of said metal, and means for guiding the valve relatively to the cylinder, substantially as set forth. 75
9. A machine for making printers' leads and rules comprising a melting pot, a chamber, a cylinder leading into the chamber, means for forcing metal from the pot into the chamber through said cylinder, a floating valve at the lower end of the cylinder for preventing return movement of said metal, means for guiding the valve relatively to the cylinder comprising a rod extending across the chamber, and a spur on the rod extending into an opening in the valve, substantially as set forth. 80
10. In a machine for making printers' leads and rules, a melting pot, a chamber therein, a plurality of cylinders leading to the chamber, pistons in the cylinders for forcing molten metal from the pot into the chamber, and means for operating the pistons comprising a camshaft, connections from the cams to the pistons including rockarms engaging the cams, and springs to maintain such engagement, substantially as set forth. 90
11. A machine for making leads and rules comprising a melting pot, a chamber therein, a cylinder leading to the chamber, a mold communicating with the chamber, a threaded orifice in the bottom of the chamber leading to the mold said orifice being in line with the cylinder, and a threaded rod constructed and arranged to be inserted through said cylinder and to be screwed into said threaded orifice, substantially as set forth. 100
12. A machine for making leads and rules comprising a melting pot, means for ejecting molten metal downward from the pot in a continuous stream, and a mold attached to the bottom of the pot to shape the metal so ejected, said mold having a vertical passage in line with a port in the pot substantially as set forth. 110
13. A machine for making leads and rules comprising a melting pot, means for ejecting molten metal from the pot in a continuous stream, a mold attached to the bottom of the pot for shaping the metal so ejected, and means for cooling the mold, substantially as set forth. 120
14. A machine for making leads and rules comprising a melting pot, means for ejecting molten metal from the pot in a continuous stream, and a mold detachably secured to the pot below the level of the molten metal, said mold having a straight passage 125
15. A machine for making leads and rules comprising a melting pot, means for ejecting molten metal from the pot in a continuous stream, and a mold having a straight passage 130

in line with a port in the bottom of the pot substantially as set forth.

15. A machine for making leads and rules comprising a melting pot, means for ejecting molten metal from the pot in a continuous stream, a mold detachably mounted on the pot below the level of the molten metal, and means for adjusting the mold without removing it from the pot to vary the thickness of the product, substantially as set forth.

16. A machine for making leads and rules comprising a melting pot, means for ejecting molten metal from the pot in a continuous stream, a mold to shape the metal so ejected comprising an apertured block lying flat against the bottom of the pot, a pair of longitudinal side members secured directly to said block, and a pair of blocks between said side members providing between them an elongated mold chamber open at the lower end, substantially as set forth.

17. A machine for making leads and rules comprising a melting pot, means for ejecting molten metal from the pot in a continuous stream, a mold to shape the metal so ejected comprising an apertured block lying flat against the pot, a pair of longitudinal side members secured to said block, and a pair of blocks between said side members providing between them an elongated mold chamber one of said blocks being adjustable toward and from the other, substantially as set forth.

18. A machine for making leads and rules comprising a melting pot, means for ejecting molten metal from the pot in a continuous stream, a mold receiving such metal, said mold comprising a block forming one side of a mold chamber, holes in the block adapted to register with holes in the adja-

cent parts of the mold whereby the thickness of the product may be adjusted without interruption of the work, and means for securing the block in adjusted position, substantially as set forth.

19. A device for shaping fluid metal comprising a melting pot having a closed chamber therein below the level of the metal, a die immediately below the pot, and a port leading through the bottom of the pot from the chamber to the die, said die having a straight molding passage in line with said port.

20. A device for shaping fluid metal comprising a melting pot, a closed chamber, a plurality of cylinders communicating at their lower ends with said chamber, pistons in the cylinders, means to force the pistons yieldingly downward, means to prevent return of the metal, and a die connected to said chamber.

21. A device for shaping fluid metal comprising an open melting pot having a closed chamber, therein below the level of the metal, in the chamber, and a molding passage extending in a right line from said chamber to the atmosphere.

22. A machine for making printers' leads and rules comprising a melting pot, a closed chamber below the normal level of the molten metal, a plurality of cylinders extending through the upper wall of the chamber, pistons in the chambers, levers pivoted at one side of the pot, and means for operating the levers in sequence, said means being at the side adjacent the pivots of the levers.

In witness whereof, I have hereunto set my hand at Washington, District of Columbia, this 17th day of March, A. D. nineteen hundred and twenty-five.

GEORGE H. M. DAHL.
